UNITED STATES PATENT OFFICE.

SAVO B. LJUTICA, OF PORTLAND, OREGON.

FOLDING TOOTH-BRUSH.

1,006,857.

Specification of Letters Patent.

Patented Oct. 24, 1911.

Application filed February 18, 1911. Serial No. 609,387.

To all whom it may concern:

Be it known that I, SAVO B. LJUTICA, a subject of the Porte of Montenegro, who have obtained my first papers in the matter of becoming naturalized in the United States, and a resident of Portland, in the county of Multnomah and State of Oregon, have invented a new and Improved Folding Tooth-Brush, of which the following is a full, clear, and exact description.

My invention relates to tooth brushes, and it has for its object to provide one which may be folded and carried in the pocket, the device having a box for containing tooth powder, which is permitted to reach the brush member, pivoted to the box, through an opening therein.

Additional objects of the invention will appear in the following complete specification, in which the preferred form of my invention is disclosed.

In the drawings similar characters of reference indicate corresponding parts in all the views, in which—

Figure 1 is a perspective view showing the device in a closed position, a portion of the box member being broken away to show the position of the brush member; Fig. 2 is a longitudinal sectional elevation of the device with the brush member in extended position; Fig. 3 is a longitudinal sectional view of the device in an inverted position, and with the brush member inclosed between the extending sides of the casing; Fig. 4 is a sectional view on the line 4—4 of Fig. 3; Fig. 5 is a plan view of Fig. 2; and Fig. 6 is a perspective view showing the slide with its shank.

By referring to the drawings it will be seen that a casing 5 is provided, in the shape of a box member, having an opening 6, which is closed by a removable end member 7, the sides 8 of the box being extended beyond the box wall 9, as at 8^a, there being an opening 10 in the said wall 9. At one end of the device the extending walls 8^a are connected by an end piece 11, a brush member 12 being mounted on a pivot 13 which connects the extending walls 8^a at the other end of the device. The brush member 12 has flattened surfaces 14, and 15, in close proximity to the pivot 13. A cylindrical member 16 is disposed between the extending sides 8^a, and being adapted to engage these flattened surfaces 14 and 15. A spring 17 is disposed in the cylindrical member 16,

and presses against a head 18, which forms a part of the said cylindrical member 16. A slide 19 is provided for closing the opening 10, this slide 19 having a shank 20, 60 which is disposed within the coils of the spring 17. Secured to the sides of the slide 19, there are buttons 21, which extend through slots 22 in the extending sides 8^a of the device. 65

When the brush member 12 is folded, and is disposed between the extending sides 8^a, the back of the brush member serves as a cover for the compartment formed by the extending sides 8^a, the end wall 11, and the 70 surface 14 of the brush member.

It will be seen by referring to Fig. 2 of the drawings, that the spring 17 not only presses against the head of the cylinder 16, but it also presses against the shank 20 at 75 the slide 19, and it therefore serves not only to hold the brush member 12, yieldingly in a predetermined position, but it also serves to hold the slide 19 yieldingly closed.

When it is desired to use the invention, 80 the buttons 21 are moved, carrying with them the slide 19, so that the opening 10 is uncovered, and when the device is inverted as shown in Fig. 3 of the drawings, the tooth powder 23, contained in the box 85 portion of the casing 5, is permitted to flow through the said opening to the brushes 24 of the brush member 12. A slight movement of the buttons 21 is sufficient to permit sufficient of the tooth powder to reach the bristles 90 24. When the tooth powder has been deposited on the bristles 24, the brush member 12 is opened, and is disposed in extended position, as shown in Fig. 2 of the drawings, when the device may be used in the ordinary 95 manner. When the user has finished cleansing his teeth, the brush is washed, and the brush member is folded between the extending sides 8^a.

Having thus described my invention, I 100 claim as new and desire to secure by Letters Patent:

1. In a folding tooth brush a casing having a compartment with sides extending beyond a wall of the compartment, there being a slot in one of the extending sides, and an opening in the said wall of the compartment, a brush member pivoted to the casing and normally disposed between the sides, a cylinder disposed between the extending sides, and pressing against the brush member, a spring disposed in the cylinder, a slide

for closing the opening having a shank disposed in engagement with the spring, and a button on the slide extending through the slot in the extending side.

- 5 2. In a folding tooth brush, a casing having a compartment with sides extending beyond a wall of the compartment there being a slot in one of the extending sides, and an opening in the said wall of the compartment, a slide for closing the opening, a button on the slide extending through the slot in the extending side, a brush member pivoted to the casing and normally disposed between the sides, and resilient means for holding the brush member and the slide yieldingly in predetermined positions.
- 10 3. In a folding tooth brush a casing having walls forming a compartment with an opening, a brush member pivoted to the cas-

ing, a cylinder disposed against the brush member, a spring disposed in the cylinder, and a slide for closing the opening, having a shank disposed in engagement with the spring.

- 15 4. In a folding tooth brush a casing having a compartment with an opening, a slide for closing the opening, a brush pivoted to the casing, and resilient means disposed between and pressing against the slide and the brush, for holding the slide and the brush yieldingly in predetermined positions.

In testimony whereof I have signed my name to this specification in the presence of two subscribing witnesses.

SAVO B. LJUTICA.
